F. H. DICKSON

KNIFE HEAD AND MANUFACTURE OF THE SAME

Filed Jan. 2, 1926

Patented Feb. 22, 1927.

1,618,920

UNITED STATES PATENT OFFICE.

FRANK H. DICKSON, OF AUBURN, NEW YORK, ASSIGNOR TO HENRY & ALLEN, OF AUBURN, NEW YORK.

KNIFE HEAD AND MANUFACTURE OF THE SAME.

Application filed January 2, 1926. Serial No. 78,892.

This invention relates to the cutting mechanism of mowing machines and has special reference to the manufacture of the knife head which connects the pitman with the cutter bar, the object of the invention being the economical production of a forged steel knife head. This object I attain in the manner hereinafter fully described, and illustrated in the accompanying drawing.

10 In the drawing, Figure 1 is a plan view of a forged knife head blank,

Figure 2 is an edge view of the same, partly in section,

15 Figures 3 and 4 are, respectively, an end and a side view of the ball member.

Figure 5 is a side view of the knife head blank or body and the ball member assembled therewith but not upset,

20 Figure 6 is a sectional view showing the assembled members in position in a holder for upsetting,

Figure 7 is a section on the line 7—7 of Fig. 6,

25 Figures 8, 9 and 10 are, respectively, a plan view, a side view, and an end view of the completed knife head, and

Figure 11 is a view showing the ball member provided with a plurality of studs.

According to the present invention, there 30 is produced the main forging 1 having the usual elongated shank 2, the vertical rib 3, and the laterally-projecting flange portion or base 4. An opening 5 is formed through the base or flange portion 4 and the vertical rib 3 terminates short of this opening, as shown clearly in Fig. 1. There is also produced by forging a ball member 6 having a spherical head 7, a fin or stem 8 extending radially from the head, and a base 9 which 35 is united with one edge of the stem and projects from the opposite sides of the same.

40 Referring to Fig. 2, it will be noted that the wall of the opening 5 is flared or beveled in opposite directions from its middle toward the opposite faces of the flange portion 4 of the knife head blank. It will also be noted, on reference to Figures 3 and 4, that the stem 8 of the ball member is relatively thin and flat-sided while the expanded 45 base 9 has an upper portion 10, the edge of which is beveled, and a lower stud portion 11 of uniform diameter. The stem 8 also has a lateral elongation or extension 12 which is adapted to overlap the end of the 50 rib 3 and may be pinned or riveted thereto.

The dimensions of the base portion or block 9 of the ball member are such that when it is engaged in the opening 5 the beveled part 10 will seat snugly in the upper bevel of the opening while the stud 11 will project 60 through and depend below the same, as shown in Fig. 5, the stock in the stud being sufficient, when upset, to completely fill the lower beveled half of the opening. Instead of providing the base of the ball member 65 with a single stud 11, the same may be provided with a plurality of studs 11^a as shown in Figure 11, and the flange or base portion 4 of the main forging 1 will of course be provided with a suitable number of holes to 70 receive said studs. The two studs 11^a and the holes in the base 4 to receive them may be comparatively small, so that one of said holes may not be located so close to the edge 75 of the base 4 of the forging 1 as to sacrifice strength.

80 Preferably, the ball member is heated and is placed, inverted, in a holding die 13, as shown in Figures 6 and 7, with the head forging or body resting on the flat upper surface of the die around the stud. The die includes a movable member 14 slidably mounted in its main body portion, and the two members of the die have their opposed faces so shaped as to produce a spherical 85 socket receiving the ball or sphere 7 and a groove accommodating the stem 8 and the rib 3. After the assembled parts have been firmly clamped in the die, a hammer 15 or other device is caused to strike or exert pressure upon the upper end of the stud 11, upsetting the same and securely uniting the ball member and the head member. The upset stud will be flush with the flange portion 90 of the head and will be securely locked thereto by reason of the double-bevel or other inter-engaging formation originally given the parts.

95 It is to be understood that while hot riveting is preferred, the two members may be 100 united by cold riveting, welding, brazing, or by any other method which will intimately join the parts, and that the double-bevel formation is only a preferred inter-engaging construction whereby the stud of the ball member will be locked in the opening in the body or head member.

105 Having fully described my invention what I claim as new and desire to secure by Letters-Patent, is:—

1. The process of forming a knife head which consists in forging a head member with a flange portion and an opening through said portion having a double-bevel wall, 5 forging a ball member with a base having a beveled portion to seat upon one bevel of the opening and a stud to project beyond the other bevel of the opening, and upsetting the stud against the last-mentioned bevel.
  - 10 2. The process of forming a knife-head which consists in forging a head member with an opening therethrough having both ends flared, forging a ball member with a stem and a base, supporting the ball member 15 in inverted position with its base extending through the opening in the head member, and upsetting the base of the ball member to fill the opening in the head member.
  - 20 3. The process of forming a knife-head which consists in forging a head member with a flange portion having an opening therethrough and a rib terminating short of the opening, forging a ball member having a stem, a sphere at one end of the stem, and 25 a base at the opposite end of the stem, securing the ball member in inverted position with the base extending through the opening in the head member and the stem overlapping the rib of said member, upsetting the 30 base of the ball member upon the head member, and joining the stem of the ball member with the rib of the head member.
  - 35 4. The process of forming a knife head which consists in forging a head member with a flange portion and an opening therethrough, forging a ball member with a lateral stud to engage through the opening, and simultaneously locking the stud in the opening and intimately uniting it with the flange 40 portion of the head member at the opening,
- the ball being thereby mounted in spaced relation to the flange.
5. A forged knife head comprising a head member having an opening and a ball member having a radial stud entering said opening and rigidly secured therein whereby said ball member is rigidly secured to the head member at said opening with the ball spaced from the head member. 45
  6. A forged knife-head comprising a head member having a rib and an opening adjacent the end of the rib, and a ball member having a stem joined to said rib and a base upset in the opening. 50
  7. A forged knife-head comprising a head member having an opening therethrough with both ends of the opening flared and a rib terminating short of said opening, and a ball member having a stem projected laterally and united with the rib and a base 60 upset in the flared ends of the opening. 65
  8. Means for producing forged knife-heads including clamping members presenting a spherical socket and a groove leading therefrom to receive the rib of a head member and the sphere and stem of a ball member assembled with the head member, and a pressure device cooperating with the clamping members to upset the end portion of the stem of the ball member. 70
  9. A forged knife head comprising a head member having an opening therethrough, and a ball member having a radial shank locked in said opening and intimately united with the head member at the opening, the ball being spaced from the head. 75

In testimony whereof, I have signed this specification.

FRANK H. DICKSON.
